UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

LOOPER MECHANISM FOR SEWING-MACHINES.

1,243,145.

Specification of Letters Patent. Patented Oct. 16, 1917.

Application filed December 12, 1914. Serial No. 876,763.

To all whom it may concern:

Be it known that I, ALBERT H. DE VOE, a citizen of the United States, residing at Westfield, in the county of Union and State 5 of New Jersey, have invented certain new and useful Improvements in Looper Mechanism for Sewing-Machines, of which the following is a specification, reference being had therein to the accompanying drawings.

10 This invention has for its object to provide looper mechanism for sewing machines and more particularly machines adapted for glove sewing and similar uses.

The improvements may be used in conjunction with needle actuating and feeding mechanisms of any suitable form, the improvements being especially adapted, however, to the general machine construction shown and described in my application filed 20 October 18, 1913, Serial No. 795,841, in which the reciprocating needle-bar is provided with a transverse pin slidingly fitted within the boss of a strap embracing an actuating eccentric upon the rotary driving 25 shaft, the feeding mechanism comprising a horizontally arranged feed-wheel carrying a plurality of ratchet-wheels of progressively smaller diameters operatively engaged by one of a series of selective pawls 30 carried by a pawl block.

The looper mechanism of the present improvements comprises a vibratory and endwise movable looper-bar carrying a looper at one end and pivotally connected at the 35 opposite end with a rocking element fulcrumed upon a swinging arm and carrying studs upon opposite sides of its fulcrum point engaging actuating cams from which the rocking element derives both rocking 40 and bodily reciprocating movements upon its supporting fulcrum. Intermediate its ends the looper-bar is slidingly mounted in a tilting bearing having a fulcrum in one arm of a bell-crank lever which has a lateral 45 arm connected by a pitman with a swinging lever actuated by a cam upon said driving shaft.

The mechanism thus briefly described imparts to the looper the requisite six-motioned 50 travel required in the class of overseaming mechanism to which the present improvement more particularly relates, the movements being effected through actuating cams which are without harsh or abrupt shoulders.

In the accompanying drawings, Figure 1 is a side elevation, partly in section, of a machine embodying the present improvements, and Fig. 2 is a top plan of the same. Figs. 3 and 4 are detail perspective views 60 of certain connected parts of the improvements.

The improvements are shown mounted within a frame comprising the hollow base 1 from which rises the standard 2 provided 65 with the transverse main or driving shaft 3 and the cross shaft 4 disposed above and parallel with the same. Adjustably secured upon the main shaft 3 is the gear-wheel 5 provided in one face with the cam-groove 6 and in the opposite face with the cam-groove 7 and meshing with the gear-wheel 8 similarly secured by means of the set-screw 8' upon the shaft 4 and having the cam-groove 9 in the face corresponding with 75 that of the gear 5 containing the cam-groove 6.

Mounted within the standard 2 upon the cross pin 10 is the hub 11 of a swinging arm 12 having journaled in the boss 13 at its 80 upper end a fulcrum pin 14 extending laterally from a cruciform rocking or cam follower element having upwardly extending and depending arms 15 and 16 carrying respectively the roller studs 17 and 18 which 85 enter the cam-grooves 9 and 6 respectively. The said rocking element is provided with lateral arms 19 and 20 carrying screw-studs 21 entering slots 22 in a plate 23 which is provided at its forward end with the laterally offset extension 24 provided with the bearing boss 25.

Journaled in the bearing boss 25 is the pivotal pin 26 formed with the forked end 27 in which is pivotally secured by means 95 of the pin 28 the apertured extremity of the split socket 29 in which is secured by means of the clamp-screws 30 the rearward end of the looper bar 31 having fitted upon its forward end the looper socket 32 secured 100 thereon by means of the set-screw 33 and having fastened therein by means of the set-screw 34 the shank 35 of the looper which is represented as formed with the eye-pointed blade 36.

The looper bar is slidingly journaled intermediate its ends in the tilting bearing sleeve 37 which is pivotally sustained by means of the screw-pin 38 between the spaced ears 39 of a block formed in the head of a rocking 11

pin 40. The pin 40 is journaled within the bearing boss 41 on one arm 42 of a rocker formed with a second angularly disposed arm 43 and fulcrumed by means of the stud-screw 44 upon a lateral ear 45 extending from the collar 46 secured by means of the cross pin 47 and set-screw 48 upon the reduced end 49 of a block 50 which is fitted within the apertured boss 51 of the standard 2.

10. Journaled upon the shaft 4 is the apertured boss 52 of a swinging lever 53 carrying a roller-stud 54 entering the cam-groove 7 of the gear-wheel 5 and having a laterally offset extension 55 carrying the ball-stud 56. The ball-stud 56 is embraced by a strap 57 at one end of a short pitman 58 having at its opposite end a strap 59 which embraces a ball-stud 60 carried by the rocker-arm 43.

15. 20. As will be observed by reference to Fig. 1, the looper actuating cam-grooves 6 and 9 are of different shape and are so formed that the entering studs 17 and 18 of the rocking element are caused to perform differentially timed reciprocatory movements whereby the rocking element is given not only rocking movements upon its supporting fulcrum stud 14, but receives bodily movements lengthwise of the looper-bar which, 25 through the pivotal connection 28 therewith, communicate to the adjacent end of the looper-bar endwise reciprocatory and vibratory movements in a vertical direction. By its described connections with the cam element 5, the rocker 42 43 communicates to the bearing sleeve 37 and hence to the looper-bar movements crosswise of its length or endwise of the looper blade 36.

30. 35. By the described connections and mountings of the various parts it is evident that ample provision is made for adjustment of the various looper positions and timing of its several movements, and the construction and arrangement of the parts and connections enable the machine to be operated at high speeds without excessive friction and wear.

Having thus set forth the nature of the invention, what I claim herein is:—

40. 45. 50. 55. 60. 1. In a sewing machine, the combination with a vibratory and endwise movable looper-bar, a looper mounted thereon, and a fulcrum for said bar, of a rocking and bodily movable element pivotally connected with said bar on an axis extending transversely of said bar, and differentially timed actuating elements acting through said rocking and bodily movable element to impart vibratory and endwise movements to the looper-bar.

2. In a sewing machine, the combination with a vibratory and endwise movable looper-bar, a looper mounted thereon, and a fulcrum for said bar, of a rocking element pivotally connected with said bar on

an axis extending transversely of said bar and spaced from the axis of vibratory movement of said bar, a fulcrum for said element movable crosswise of said axis, and differentially acting actuating elements for communicating to said rocking element its rocking and bodily crosswise movements upon its fulcrum. 70

3. In a sewing machine, the combination with a vibratory and endwise movable 75 looper-bar, a looper mounted thereon, and a fulcrum for said bar, of a rocking element pivotally connected with said bar on an axis extending transversely of said bar and spaced from the axis of vibratory movement of said bar, a fulcrum for said element, a swinging arm for sustaining the fulcrum for said element, and means acting on said element independently of said swinging arm for communicating to said element its rocking and bodily crosswise movements upon its fulcrum. 80

4. In a sewing machine, the combination with a vibratory and endwise movable looper-bar, a looper mounted thereon, and a fulcrum for said bar, of a support for said fulcrum movable crosswise of said bar, a rocking and bodily movable element pivotally connected with said bar, and means for imparting operative movements to said fulcrum-support and to said element. 90

5. In a sewing machine, the combination with a vibratory and endwise movable looper-bar carrying a looper, and a fulcrum for said bar, of a rocking element, a swinging arm carrying a fulcrum upon which said rocking element is mounted, actuating means for reciprocating parts of said rocking element upon opposite sides of its fulcrum at different speeds and a pivotal connection between said looper-bar and said rocking element at a point of the latter removed from its fulcrum and from said oppositely disposed parts. 100

6. In a sewing machine, the combination with a vibratory and endwise movable looper-bar carrying a looper, and a fulcrum for said bar, of a rocking element, a movable fulcrum sustaining the same, actuating means including connections with said rocking element for imparting to the latter rocking and bodily reciprocating movements in a plane substantially parallel with said bar, a pivotal connection between said rocking element and said bar, and an operative connection independent of said connections with the rocking element between said actuating means and the looper-bar fulcrum for imparting to the latter movements crosswise of said looper-bar. 110

7. In a sewing machine, the combination with a vibratory and endwise movable looper-bar carrying a looper, means including a plurality of cam-elements and a single-cam-follower element acted upon by 120 125 130

- said cam elements for imparting said movements to the looper-bar, a looper-bar fulcrum, a support therefor movable crosswise of the looper-bar, a swinging lever 5 operatively connected with one of said cam-elements, and a connection between said swinging lever and the fulcrum support for the looper-bar for imparting sidewise movements to the latter.
- 10 8. In a sewing machine, the combination with a reciprocating needle, a vibratory and endwise movable looper-bar carrying a looper having a beak directed transversely of the needle and adapted to seize a loop of 15 needle-thread, means including a plurality of cam-elements for imparting said movements to the looper-bar, a looper-bar fulcrum, a rock-lever sustaining said fulcrum and having a pivotal support extending in a 20 direction transversely of the looper beak and needle, a swinging lever operatively connected with one of said cam-elements and a pitman connection between said swinging lever and a point of said rock-lever disposed at one side of its pivotal support.
- 25 9. In a sewing machine, the combination with a vibratory and endwise movable looper-bar carrying a looper, of a sleeve embracing said looper-bar and affording a 30 fulcrum therefor, supporting means for said sleeve adapted to permit movement of the latter in a direction crosswise of the looper-bar, a rocking element pivotally connected with the looper-bar rearwardly of said sleeve, a movable fulcrum for said rocking 35 element, and means for imparting movements to said rocking element both bodily with its fulcrum and relatively to the latter.
10. In a sewing machine, the combination with a vibratory and endwise movable 40 looper-bar carrying a looper, of a tilting bearing within which the looper-bar is slidably mounted, means for moving said bearing in a direction crosswise of the looper-bar, a rocking element pivotally connected 45 to the looper-bar, a swinging arm upon which the rocking element is fulcrumed, studs carried by said rocking element upon opposite sides of its fulcrum point, and actuating cams engaging said studs and 50 adapted to impart to the rocking element bodily reciprocating movements, and rocking movements upon its fulcrum.

In testimony whereof, I have signed my name to this specification, in the presence 55 of two subscribing witnesses.

ALBERT H. DE VOE.
